DESIGN FOR A COFFEE PITCHER

Alfred F. Fukal, Chicago, Ill., assignor to Chicago
Flexible Shaft Company, Chicago, Ill., a corporation of Illinois

Application December 1, 1933, Serial No. 49,914

Term of patent 7 years

To all whom it may concern:

Be it known that I, ALFRED F. FUKAL, a citizen of the United States, residing at Chicago, in the county of Cook and State of Illinois, have invented a new, original, and ornamental Design for a Coffee Pitcher, of which the following is a specification, reference being had to the accompanying drawing, forming part thereof.

In the drawing:

I claim:

The ornamental design for a coffee pitcher,
substantially as shown.
